4 Claims. (Cl. 51—123)

This invention relates to mechanisms intended especially for machines for grinding or polishing involute gear teeth of the type in which the rolling movement between the work-piece and the tool is not uniform.

If, when an involute gear tooth is produced, the rolling velocity of grinding is kept constant, there are produced differently large longitudinal sections of the involute in the same period of time. The longitudinal sections become larger when the distance from the rolling circle increases and the tooth flanks are not ground accurately. It has for this reason become necessary to adjust the rolling velocity during the grinding operation in such a manner that the tooth heads are ground satisfactorily which entails, however, the drawback that the tooth flank portions lying in the proximity of the rolling circle are being ground too slowly, or uneconomically.

In machines with two grinding disks for abrading involute gear teeth it is known to give said disks a variable rolling movement relatively to the tooth profile in such a manner that the disks act on approximately equal profile lengths per unit of time. In order to attain this particular rolling movement cams are used in these machines.

An object of the present invention is to provide a device which renders possible alterations of the rolling movement of the work-piece relatively to the tool by simple means, without the employment of expensive cams.

The chief characteristic feature of the invention is that for the production of irregular rolling movement a slot and crank device is provided, the appertaining crank of which performs a uniform reciprocating motion.

Changes in the rolling movement can be obtained, according to this invention, by adjusting the point where the oscillating arm engages a slide acting on the work-piece carrier.

The invention is illustrated diagrammatically and by way of example in the accompanying drawings in which Figure 1 is a plan of one constructional form designed according to this invention. Figure 2 is a similar representation showing another constructional form, and Figure 3 is a similar representation showing a third constructional form, all as fully described hereinafter.

Referring to Fig. 1, 1 denotes a base frame provided with guide members 3 on which a slide 2 can be reciprocated. On the slide 2 is a supporting member 4 for the work-piece to be dealt

with which is, in the example shown, a gear wheel r . The carrier 4 with the gear wheel r are rotatably supported on the slide 2, and connected with the carrier 4 is, in the example shown, a disk 5 around which a band 6 extends, the ends of which are affixed to the frame 1 of the machine.

Moving the slide 2 to and fro, together with the parts it carries, relatively to a grinding disk 7 which is moved up and down in the direction of the teeth gap and is shaped at its rim like a rack tooth, is effected by means of the following mechanism:

In the frame of the machine is supported on 15 a pivot 9 an upwardly extending arm 8 having a slot 10 engaged by a pin 11 projecting from a female screw 12 supported upon a threaded spindle 13. This spindle is uniformly turned alternately in one and in the other direction, where- 20 by the arm 8 is oscillated correspondingly by the members 11 and 12. The arm 8 is provided with a pin 14 engaging a slot 15 of a horizontal lever 16 connected with the slide 2.

In the position shown in Fig. 1 the slotted arm 8 is in its middle position in which the pivot 14 is located at the point 5. The circular curve represents the path of said pivot and is provided with the numerals 0 to 10. It will be noted that the female screw 12 has been moved with uniform velocity from the position corresponding to the numeral 0 on the spindle 13 to the position corresponding to the numeral 5 thereof. The movement of the pin 14 is transmitted to the lever 16, as well as to the slide 2 with which it is connected, by the slot 15 of the first-mentioned slide, but owing to the pin 14 moving through a curved path the movement of the slides 16 and 2 is not uniform, but unequally accelerated and moved to an extent corresponding to the distance between the points 0 and 5, and thus the gear wheel r is turned with unequal velocity in the distance between the points 0 and 5, shown on the generating circle b . The tangents drawn through all said points 0 to 5 show that while the unequal rolling movement of the wheel r is effected the grinding disk 7 will have acted on nearly equal profile sections of the tooth flank a during equal periods of time in which the threaded spindle 13 is uniformly turned.

50 While the female screw 12 is further moved to the right by the spindle 13 so as to pass the points 6 to 10 the rotary motion of the wheel r is unequally retarded so that during this time the grinding disk 7 has likewise acted on nearly equal profile sections of the tooth flank a .

I wish it to be understood that I do not limit my invention to constructional forms in which both tooth flanks are ground during one rolling stroke. It is quite possible to vary the construction in such a manner that only one flank is acted on by the grinding disk during one rolling stroke.

In the modification shown in Fig. 2 the arm 8¹ is moved in such a manner that it moves with constant angular speed on the circularly curved path 0 to 10. For the rest, the construction is the same as in Fig. 1.

In both forms of construction according to Figs. 1 and 2 the bearing bracket 17 of the pivot 9 and the pin 14 of levers 8 and 8¹ respectively are adjustably mounted, in order to change the ratio of movements.

In the modification illustrated in Fig. 3 the arrangement of the parts is such that the rolling movement varies with respect to the arrangements shown in Figs. 1 and 2, the object being in this case to grind the head portion of the tooth flank more slowly than the foot portion.

The threaded spindle 13 is also in this case turned with uniform speed so that the nut 12 covers equally long paths in equally long periods of time. The intermediate members transmitting the motion from the spindle 13 to gear 7 provide an unequal rolling movement of the gear wheel. The tangents extending through the points 0 to 5 of the generating circle b show that unequal rolling motion of the wheel 7 takes place during equal periods of time in which the uniform driving movement of the nut 12 continues along the path 0 to 5 and the abrasive disk 7 thus grinds smaller profile sections on the head of the tooth than on the foot portion of the tooth. When the nut 12 is further moved (to the right) along the path 5 to 10 the movement of the wheel 7 is unequally retarded, and it appears from the tangents on the points 5 to 10 of the generating circle b that the grinding disk 7 acts also during this part of the rolling path on smaller profile sections on the head portion of the tooth flank a¹ than on the foot portion of the tooth flank a² during the same interval of time.

I claim:

1. In apparatus for generating involute gear teeth of gear wheels, a frame, a member slideable on the frame, a gear blank rotatably mounted on said slide member, a disc rotatable with the gear blank, a band extending around said disc with the ends thereof fixed with respect to the frame, a disc-shaped cutting tool arranged for generating gear teeth on the gear blank, a longitudinally movable lever connected to the slide member extending therefrom in the direction of movement of the slide member, said lever having a transverse slot therein, a pivotally mounted arm arranged transversely of said lever, a pin carried by said arm engaging said lever within said slot, and means for swinging said arm.

2. In apparatus for generating gear teeth, a frame, a member slideable on the frame, a gear blank rotatably mounted on said member, means for rotating the gear blank during sliding movement of said member, a disc-shaped cutting tool arranged for generating gear teeth on the gear blank, a longitudinally movable lever connected to said slide member, said lever having a transverse slot therein, a pivotally mounted arm, a pin carried by said arm engaging said lever within said slot, means for swinging said arm, and means movable transversely of the movement of said lever for adjusting the pivoting position of said arm on said frame.

3. In apparatus for generating involute gear teeth of gear wheels, a frame, a member slideable on the frame, a gear blank rotatably mounted on said slide member, a disc rotatable with the gear blank, a band extending around said disc with the ends thereof fixed with respect to the frame, a disc-shaped cutting tool arranged for generating gear teeth on the gear blank, a longitudinally movable lever connected to the slide member extending therefrom in the direction of movement of the slide member, said lever having a transverse slot therein, a pivotally mounted arm arranged transversely of said lever, a pin carried by said arm engaging said lever within said slot, and a threaded spindle arranged substantially parallel with respect to said lever for swinging said arm.

4. In apparatus for generating gear teeth, a frame, a member slideable on the frame, a gear blank rotatably mounted on said member, means for rotating the gear blank during sliding movement of said member, a disc-shaped cutting tool arranged for generating gear teeth on the gear blank, a longitudinally movable lever connected to said slide member, said lever having a transverse slot therein, a pivotally mounted arm, a pin carried by said arm engaging said lever within said slot, said arm having a longitudinally extending slot therein, a threaded spindle arranged transversely of said arm, a nut member threaded on said spindle, and a pin carried by said nut member engaging said arm within the slot thereof.

ERICH PARZ.
